(57) **CLAIM**

The ornamental design for a golf shoe outsole, as shown and described.

DESCRIPTION

FIG. 1 is a lateral side perspective view of the first embodiment of the golf shoe outsole showing our new design;

FIG. 2 is a lateral side view thereof;

FIG. 3 is a medial side view thereof;

FIG. 4 is a top plan view of thereof;

FIG. 5 is a bottom plan view thereof;

FIG. 6 is a front elevation view thereof;

FIG. 7 is a rear elevation view thereof;

FIG. 8 is a lateral side perspective view of the second embodiment of the golf shoe outsole;

FIG. 9 is a lateral side view thereof;

FIG. 10 is a medial side view thereof;

FIG. 11 is a top plan view thereof;

FIG. 12 is a bottom plan view thereof;

FIG. 13 is a front elevation view thereof; and,

FIG. 14 is a rear elevation view thereof.

In FIGS. 1-14, the broken lines on the top surface of the shoe including laces and logo depict environment and form no part of the claimed design. Also, the broken lines on the outsole, including the logo, depict environment and form no part of the claimed design.

1 Claim, 10 Drawing Sheets
